UNITED STATES PATENT OFFICE.

THOMAS B. JEFFERY, OF CHICAGO, ILLINOIS.

TUBULAR-FRAME JOINT.

SPECIFICATION forming part of Letters Patent No. 575,353, dated January 19, 1897.

Application filed May 16, 1895. Serial No. 549,488. (No model.)

To all whom it may concern:

Be it known that I, THOMAS B. JEFFERY, a citizen of the United States, residing at Chicago, county of Cook, and State of Illinois, have invented and used certain new and useful Improvements in Tubular-Frame Joints, which are fully set forth in the following specification, reference being had to the accompanying drawings, forming a part thereof.

10 The purpose of this invention is to provide an improved means for rigidly joining the tubular parts of frames such as are commonly employed for velocipedes, avoiding the necessity of making apertures for screws or rivets

15 or other similar fastenings, and avoiding also the necessity of heating the tube to so high a degree as would be necessary for the purpose of brazing or brass-soldering and at the same time obtaining a perfectly-reliable junction

20 and stiff joint with the minimum weight.

In the drawings, Figure 1 is a side elevation of a bicycle-frame with the position of the wheel suggested. Fig. 2 is an enlarged section at the line 2 2 on Fig. 1. Fig. 3 is a detail section at the line 3 4 on Fig. 2, looking in the direction of the arrow 3, showing a side elevation of the joint at the crank-axle bearing. Fig. 4 is a section at the line 3 4 on Fig. 2, looking in the direction of the arrow 4. Fig. 5 is a view similar to Fig. 3, but illustrating a slight modification in respect to the form of the long socket in the junction-piece. Figs. 6 and 7 are perspectives of joint-fittings involving this invention, having modified forms of the long socket for a tubular arm of the frame.

The characteristic element in this invention is a novel junction-piece or joint-fitting, which may be of metal tubing and is preferably made out of steel tubing formed in the manner which will be described for the several joints, respectively.

I have shown such a junction-piece in the various forms required at the different joints of a bicycle-frame of familiar type, and I will now describe these several junction-pieces and in such description point out the characteristics of my invention.

The most difficult and most important joint 50 on a bicycle-frame of the general pattern shown in Fig. 1 is that which occurs at the lower angle of the frame, from which two arms

diverge upwardly, the one to the steering-head or junction with the bearing of the front fork and the other to the junction with the 55 bracing-fork which strides the rear wheel, this joint being the one at which the pedal-crank shaft is journaled. To form this joint, I employ, preferably, a piece of steel tubing A, which is bent to form an elbow having the 60 proper angle of the frame at this joint. This elbow is apertured sideward, that is, in a plane at right angles to the plane in which it is bent, to receive the cross-tube B, which is inserted through and protrudes from both 65 sides of the elbow, the material of which is flanged outwardly about the apertures to increase the bearing or seating surface of the cross-tube B, to which said elbow is rigidly secured by the process of brazing or brass- 70 soldering, which may be prudently employed at this joint, both on account of the shortness of the cross-tube and of the fact that it is feasible to employ for so short a piece a heavier tube than it would be desirable to 75 use for the frame in general, and because the axle passing through this and obtaining bearing in or upon it entirely removes any danger of bending it, and therefore entirely removes the objection to the employment of 80 brass solder, which requires to make it flow a heat sufficient to injure the tubing. The arms A' A² of the elbow A thus constitute two sockets, which are adapted to receive the tubular frame-bars C' C², respectively, of the 85 frame. It will be evident that these tubular frame-bars being inserted in said sockets will obtain very long contact or seat therein, and that by reason of the extent of such contact a very secure joint may be obtained with soft 90 solder, which flows at comparatively low temperature as compared with hard solder or as compared with any process equivalent to welding, and that by this means the excessive heating of the tubular frame-bars necessary 95 to make a joint with hard solder is avoided; but it is not necessary that the contact should be so extensive as it would be if the arms of the elbow were left unmitigated, that is, of full tubular form throughout their entire 100 length, and in order to lighten the joint as much as possible and at the same time retain the advantage of the extended contact to the full degree necessary, and the utmost desir-

able value of the stiffening effect of the tubular clip or elbow, as well as to distribute this stiffening effect considerably over the frame-arms extending from the joint, I cut away the 5 metal of the arms A' A², as shown at a' a³ and at a¹⁰ and a²⁰, respectively, at such lines that the stiffening strength of the clip-arm diminishes from the point where the cut commences, thence outward from the elbow, substantially 10 as the bending strain diminishes, and for the purpose, also, of distributing any strain tending to break the arm; but I leave bands or rings or clasping-fingers A¹⁰ A²⁰ near the ends 15 of said arms which completely (see Fig. 3) or nearly (see Fig. 6) surround the frame-arms C' C², respectively. By this means I retain a long and sufficiently-extended contact between the inner surface of the elbow-arms and the outer surface of the frame-arms and 20 prevent any danger of the ends A¹¹ and A²¹, respectively, parting from the frame-arms, as a point having a small contacting-surface would be liable to do in the absence of a rivet, which is undesirable, if it were not for the 25 clasps A¹⁰ A²⁰ of the original tube left to bind the clip-arm in place on the frame-arm.

I have spoken of the elbows as "tubular," the reference being to the finished form. I do not intend, however, to be limited to making it from tubing—that is, metal which is tubular at the commencement of the process—since it will be understood that sheet metal may be folded into tubular form and joined with substantially the same effect.

30 In applying the principle of construction which is involved in the joint already described to the joint which occurs where the horizontal or approximately horizontal rear fork-arms C³ C³ and the cross-tube B are connected, having no occasion to form an elbow, I merely notch the end of the tubular fitting D and flange the edges of the notch to form a saddle or seat d', fitting on the cross-tube B, and at this seat I employ hard solder, as 35 at the elbow of the fitting A, and in cutting away the metal of the socket D' to reduce its weight, while retaining a sufficient portion suitably shaped to distribute the stiffness and prevent concentration of any breaking 40 strain at the point where the socket terminates, I take into account the fact that it is important to avoid anything which will lengthen the crank-axle or spread the cranks, as would be the result of increasing the 45 diameter of the tubular frame-arms at the point where—the arms of the fork diverging slightly to embrace the wheel—one of them approaches the sprocket-wheel E, as seen in Fig. 2, and I therefore cut away the metal of the socket 50 D' of the clip D at the sides, as seen at D² D² in Figs. 2 and 1. In this clip also I leave a clasping-band D³ to prevent danger of the end of the clip parting from the tube; but I notch the ends of the socket at d³ to distribute 55 the strain on the tube.

In applying this invention to the junction of the fork-arms with the clips F F, which

make the connection with the rear axle, I cut away the sockets F' F², as seen in Figs. 1 and 2, at the outer side between the ends of the sockets at F¹⁰ and F²⁰, leaving the two bands f¹⁰ f¹⁰ and f²⁰ f²⁰ encircling the tubular fork-arms.

The form in which this invention is applied to the clip which makes the junction between the frame-arm C' and the steering-head G is seen in Fig. 1 and will be recognized as substantially the same as that which is employed in the fitting D.

At the head of the steering-fork I apply the invention in the form of the fitting H, one branch of which is seen in side elevation in Fig. 1, the other branch being similar and the whole fitting appearing in front elevation in Fig. 5. In this fitting, as will be seen by reference to the drawings, I cut away the metal from a line h parallel with the lower end of the tubular arm of the fitting, the cut at this line extending about two-thirds of the circumference, thence upward at both sides 90 with a slight forward tendency until the two edges of the cut are a little less than one hundred and eighty degrees apart and thence directly upward substantially as high as the crotch of the fork, and then extending down 95 toward the forward slide, leaving a tongue or bracing-lip H' at the front. The upper end of this fitting is shaped at H² to provide the customary ball-case for the ball-bearing joint of the head.

100 The clip K, which makes the junction between the upper horizontal frame-bar C⁴ and the steering-head G, is formed by cutting away the metal of the clip at the upper side at line k, parallel with the rear end of the clip for something over half its circumference, the cutting-line extending thence in an upwardly-inclined direction to the upper side of the clip which it intersects a short distance back of the flanges K', which form the clasp 110 by which the fitting is joined to the steering-head G.

In the modified forms of socket shown in Figs. 6 and 7, which are applicable to any of the joints, though in those figures they are 115 shown as applied to the joint at the crank-axle bearing, I have shown the clasp only partly encircling the tube near the end of the tapered terminal of the socket, but the spurs or serrations y y in a measure perform the 120 function of such clasps and also serve to give the socket an ornamental appearance.

To all the forms shown of the device which serve the purpose of preventing the danger of detachment of the tube from the tongue which constitutes the remnant of the socket I apply the term "clasp," whether that device be in a form which completely encircles the tube, as in Figs. 2 and 3, or in the form in which the tube is only partly, but more than half 130 encircled, as in Figs. 6 and 7. In all the forms in which this clasp is shown it has the function of affording increased surface for soldering without reproducing the danger of crys-

tallization from arrested vibration and of breaking by the concentration of the bending strain. When the clasp more than half encircles the tube, in addition to affording greater surface for soldering it resists detachment of the tube from the clip by its stiffness, because the fingers must be spread in order to detach the tube. When the clasp is a complete ring, its tensile resistance to rupture is added to the stiffness by which it resists bending as a further means of preventing detachment of the clip from the tube.

In all the forms in which the clasps do not extend entirely around the tubular arm of the frame the fingers or spurs which constitute such pair of clasps should be somewhat thicker than it would be necessary to make the encircling ring of which they are the substitute or rudiment, and one pair should preferably extend past the plane of the greatest width of the tube clasped, as in Fig. 7, and it may also be desirable in such cases to use a somewhat stronger grade of solder than the soft tinner's solder, which is sufficient when the socket is elongated, as shown in the longer forms illustrated and provided in the ring-clasp near the end.

The several joints shown in the frame illustrated represent three grades of junctions, the first grade comprising the junctions which may be secured by brazing, as that of the fitting A to the cross-tube B. The second grade comprises those which may be made with a solder requiring less heat than is required for brazing, but more than is required for the use of soft or tinner's solder, such, for example, as at the junctions of the arms C³ C³ with the sockets of the fitting F. The third grade of joints are those which are long enough and are otherwise adapted for the use of soft solder or tinner's solder. Of this class are the junctions of the bars C' C² of the frame and the sockets A' A² of the elbow-fitting A.

The process of brazing may be employed at joints of the first class, and tinner's solder may be employed at joints of the third class, and intermediate solder, such as silver solder, may be employed at joints of the second class where the grade of goods manufactured justifies the use of so expensive material.

I claim—

1. In a velocipede-frame, a joint between two tubular arms comprising a tubular socket to receive one of the arms of the frame, such socket being partly cut away to taper it and to diminish its area gradually toward the end; and provided with an integral narrow clasp extending in a plane transverse to the tube and more than half around the latter near the end of the taper: substantially as set forth.

2. In a velocipede-frame, the joint between two tubular arms, comprising a tubular socket to receive one of the arms of the frame: such socket being partly cut away to taper it and diminish its area gradually toward the end and provided with an integral continuous clasp completely encircling the tube in a plane

transverse thereto near the end of the taper: substantially as set forth.

3. In a velocipede, a joint between two tubular parts of the frame, one of which extends endwise toward the side of the other, in combination with such two tubular parts, a clip by which they are united comprising a seat for the side of one of said parts and a tubular socket which is adapted to receive the end of the other, said tubular socket being partly cut away between a point a short distance from the seat and a point a short distance from the end, whereby there is left standing of such socket a rudiment to receive the end of the tube, and a narrow clasp to embrace the tube near the end of the clip, and a suitable area for soldering diminishing transversely from the rudimentary socket for a distance outward toward the end of the clip: substantially as set forth.

4. In a velocipede-frame, a joint between the cross-tube which affords bearing for the crank-axle and the tubular bars of the frame, which extend endwise toward the side of said cross-tube; comprising, in combination with said tubes, a clip A comprising two tubular sockets adapted to receive the ends of the frame-bars and a transverse seat for the cross-tube, said sockets being cut away at one side between a point a short distance from the seat of the cross-tube and a point a short distance from the end of the socket: substantially as set forth.

5. In a velocipede, in combination with the front fork-arms, the fitting H adapted to form the head of the fork comprising tubular sockets H' proceeding from the head H², and adapted to receive the fork-arms respectively, such sockets being cut away at the front, the cut extending on both sides, leaving the clamping-ring h and the tongue H': substantially as set forth.

6. In a velocipede-frame, the joint between the cross-tube B and either side arm of the rear fork, comprising, in combination with said parts, a clip having a tubular socket adapted to receive the end of the fork-arm, and a transverse seat for the cross-tube B, said sockets being partly cut away to diminish their area gradually toward the end to prevent the concentration of the breaking strain, the material removed for that purpose being cut away from the sides, whereby the increase of distance between the crank-arms is prevented: substantially as set forth.

7. In a velocipede-frame, a joint between the cross-tube B and either side of the rear fork, which comprises in combination with said parts a clip having a socket to receive the end of the side arm, and a transverse seat for the cross-tube, the socket being cut away to diminish its area gradually toward the end to prevent concentration of the breaking strain, such diminution being effected by removing material at the side to prevent the increase of the spread of the pedal-cranks; a complete encircling ring D³ being left at the end to con-

nect the tongues D² left standing by cutting away the sides, the tubular socket being notched at the end at two opposite points in line with the ends of said tongues respectively; whereby the encircling ring is prevented from causing concentration of the breaking strain on the fork-arm: substantially as set forth.

In testimony whereof I have hereunto set my hand, in the presence of two witnesses, at 10 Chicago, Illinois, this 11th day of May, 1895.

THOS. B. JEFFERY.
